UNITED STATES PATENT OFFICE.

CHARLES SONNEBORN, OF WEST PITTSBURG, PENNSYLVANIA, ASSIGNOR TO PRESSED METAL RADIATOR COMPANY, OF PITTSBURGH, PENNSYLVANIA, A CORPORATION OF PENNSYLVANIA.

CLOSING-DIE.

1,151,625.

Specification of Letters Patent. Patented Aug. 31, 1915.

Application filed April 1, 1914. Serial No. 828,861.

To all whom it may concern:

Be it known that I, CHARLES SONNEBORN, a resident of West Pittsburg, in the county of Lawrence and State of Pennsylvania, 5 have invented a new and useful Improvement in Closing-Dies, of which the following is a specification.

This invention relates to dies for closing the seams of sheet metal articles.

10 The object of the invention is to provide dies for this purpose which are adjustable both longitudinally and transversely so as to adapt them for closing the seams of similar articles of different sizes and shapes, in 15 which the various parts of the die are formed in separate pieces so that each can be accurately shaped, and dies in which the wearing parts can be readily replaced when worn.

20 Another object of the invention is to provide dies of the type described which are of simple construction and in which the working faces are as free from joints as it is possible to make them and thereby avoid leaving imprints of the dies on the article being formed.

25 In the drawings, the invention is shown embodied in dies for closing, that is, pressing tightly together, the seam or joint around 30 the edges of sections of sheet metal radiators, but obviously the principle of construction of the dies may be adapted for closing the joints of various articles.

35 In the accompanying drawings, Figure 1 is a face view of one of the dies; Fig. 2 is partly a side elevation and partly a longitudinal section thereof on the line 2—2, Fig. 1; Fig. 3 is partly an end elevation and 40 partly a cross section on the line 3—3, Fig. 1; Fig. 4 is a detail view of an end steel support of a different size from that shown in Fig. 1; and Fig. 5 is a detail view of an end steel corresponding to the end steel for the support shown in Fig. 4.

45 The dies hereinafter described and shown in the drawings are used in pairs, namely, upper and lower dies, which are of identical construction, only one thereof being therefore described and shown. The dies are 50 actuated by any suitable press, the bottom die being suitably secured to the frame or bed plate of the press and the top die being carried by the vertically movable platen or press head. The means for securing these

dies to the press head and platen may be varied within wide limits. Both the top and bottom dies are of sectional or built up construction, as hereinafter described.

The bottom die shown comprises a pair of side steel supports 1, which are long bars of 60 cast iron of substantially L-shape in cross section, having a horizontal web 2 and an inner vertical wall portion 3, and preferably braced at intervals by cross webs 4. The web 2 is provided at intervals with transversely elongated slots 5 for receiving bolts 6 which are threaded into apertures 12 in a base or bolster plate 7 for securing the side steel supports thereto. Said base or bolster plate is provided with one or a plurality, 70 two being shown, of transverse grooves or channels 8, for receiving guide strips 9 which fit in registering transverse grooves 10 in the bottom faces of the webs 2 of the side steel support, and which are secured to said supports by tap screws 11 threaded through the guide strips from below into the webs 2. The base or bolster plate is provided with 75 several series of apertures 12 for the tap bolts 6, so that the side steel supports can be 80 placed at different distances from each other to accommodate radiator sections of different widths, and are held positively in parallel relation with each other by the guide strips 9 in the grooves 8 and 10. 85

The vertical walls 3 are rabbeted on their inner faces, as at 15, to receive side die members 14, which consist of long, rectangular steel bars or strips and are secured to the side steel supports by tap bolts 15^a threaded 90 into holes in said die members through elongated apertures 16 in the wall portions 3. These die members can be turned over and reversed end for end to renew the wearing edges, and can be readily replaced when 95 wholly worn out.

At each end of the die is located an end steel support 20 which is made of a length corresponding with the width of the particular radiator section being formed. The end 100 steel supports for the different sizes of radiator vary only in length, one size being shown in Fig. 1, and another for a narrower radiator section being shown in Fig. 4. Various sizes of end steel supports may be provided 105 so as to adapt the dies for a full line of various sizes and shapes of radiator section. The end steel support is substantially L-

shaped in cross section, being provided with a bottom web 21 provided at intervals with elongated bolt holes 22 for receiving tap bolts 23 which are threaded into holes 24 in the base or bolster plate for securing the end steel support thereto. The base or bolster plate is provided with several series or sets of holes 24 to enable the end steel supports to be secured thereto in various positions to accommodate radiator sections of varying length. Said base or bolster plate is also provided with a longitudinal groove or channel 25 for receiving a guide or strip 26, which fits a corresponding groove or depression 27 in the end steel support, and which is secured thereto by tap screws 28. These guide strips maintain the end steel supports in parallel relation to each other and exactly at right angles to the side steel supports in their various adjusted positions.

The horizontal web portion 21 of the end steel support has a thickened portion 29 extending crosswise of the die and at its ends having longitudinal extensions 30, the upper face of this thickened portion being a plain horizontal surface and forming a seat for an end die member 31. Said die member has a straight portion extending crosswise of the die and fitting in the corner between the thickened portion 29 and the vertical web portion 20 of the end steel support and is curved at each end to form longitudinal extensions 32 which rest on the longitudinal extensions 30 of the thickened portion of the end steel support. The curved end portions of the end die members are cut away on their inner sides, as at 33, so that their inner upper edges 34 form continuations of the edges of the side die members 15. The flat upper face of the end die member also lies in the same plane as the upper face of the side die member 15, the upper faces of the two side die members and of the two end die members forming the working faces of the die. The end die members 31 are secured to the end steel supports 20 by tap bolts 35 threaded through holes in the vertical web portions 36 of the end steel supports in the said die members.

Both the end and side steel supports are supported against lateral movement, that is, are prevented from spreading outwardly by end and side stops 40 consisting of angle members secured in the longitudinal and cross grooves in the bolster plate and provided with set screws or bolts 41 which are adjusted into contact with the outer faces or edges of the steel supports. The bolts 41 may also be used for fine adjustments of the steel supports.

By adjusting the end steel supports and the die members carried thereby toward and from each other, the dies will accommodate radiator sections of different lengths, but of the same width. To accommodate radi-

ator sections of different widths the side steel supports are adjusted across the die with reference to each other and other end steel supports of the proper width are substituted in the die. As the die members 70 wear out they can be readily replaced without dismantling the entire construction. The dies are very simple, can be accurately manufactured and enable the seams of pressed metal radiators or other articles to 75 be closed without leaving an imprint of the dies thereon. The dies also provide a continuous, flat working surface which can be of any width and therefore acts over the full surface of the seam to be closed. 80

What I claim is:

1. A die for closing the seams of sheet metal articles, comprising a base or bolster plate, side steel supports carrying side die members and each adjustable widthwise of 85 the die, and a series of interchangeable end steel supports secured to said bolster plate between the side steel supports and carrying end die members.

2. A die for closing the seams of sheet metal articles, comprising a base or bolster plate having longitudinal and transverse grooves, side steel supports carrying side die members and provided with guide strips working in the transverse grooves of the 95 bolster plate and adapted to be secured to said bolster plate in various adjusted positions, and end steel supports carrying end die members and provided with guide strips working in the longitudinal groove of said 100 bolster plate and adjustable toward and from each other.

3. A die for closing the seams of sheet metal articles, comprising a base or bolster plate, side steel supports secured thereto and provided with side die members, end steel supports located between the side steel supports and provided with end die members, each of said end steel supports being independently adjustable lengthwise of the die 110 and each of said side supports being independently adjustable widthwise of the die. 105

4. A die for closing the seams of sheet metal articles, comprising a base or bolster plate, side steel supports carrying side die members and each arranged to be secured to said base plate in adjusted position widthwise thereof, and end steel supports located between the side steel supports and provided with end die members. 118

5. A die for closing the seams of sheet metal articles, comprising a base or bolster plate, side steel supports carrying side die members and secured to said base or bolster plate, end supports provided with guide strips working in the longitudinal groove of said bolster plate and independently adjustable toward and from each other thereon, and end die members carried thereby having flat working surfaces in the same plane as 125 130

the working surfaces of the side die members.

6. A die for closing the seams of sheet metal articles, comprising a base or bolster plate, side die members secured thereto, end steel supports extending crosswise of the die between the side die members, and curved end die members carried by said end steel supports, said end die members being independently adjustable toward and from each other upon said bolster plate.

7. A die for closing the seams of sheet metal articles, comprising a base or bolster plate having transverse grooves, side steel

supports carrying side die members and provided with guide strips working in the transverse grooves of the bolster plate and arranged to be secured to said bolster plate in various adjusted positions, and end steel supports carrying end die members and arranged transversely between said side supports.

In testimony whereof, I have hereunto set my hand.

CHARLES SONNEBORN.
